UNITED STATES PATENT OFFICE.

WILLIAM C. STROWBRIDGE, OF HARTFORD CITY, INDIANA, ASSIGNOR OF ONE-HALF TO
L. E. WERRY, OF HARTFORD, INDIANA.

GASOLINE FILTER.

Application filed January 19, 1921. Serial No. 438,401.

To all whom it may concern:

Be it known that I, WILLIAM C. STROWBRIDGE, a citizen of the United States, residing at Hartford City, in the county of 5 Blackford and State of Indiana, have invented certain new and useful Improvements in Gasoline Filters, of which the following is a specification.

This invention relates to a filter which is 10 especially designed for use with internal combustion engines and has for its purpose to assure a clean supply of gasoline to the carburetor, the filter being interposed in the pipe line leading from the gasoline supply 15 tank to the carburetor.

The invention has for its object to provide a simple and efficient filter of this kind which can be readily installed, and which is so constructed that it can be easily taken 20 apart for cleaning, repairs, etc.

With the objects stated in view, the invention consists in the novel combination and arrangement of parts to be hereinafter described and claimed, and in order that the 25 same may be better understood reference being had to the accompanying drawings, forming a part of this specification.

In the drawing:—

Figure 1 is a central longitudinal vertical 30 section through the filter,

Figure 2 is a transverse central vertical section taken through the filter, and

Figure 3 is a fragmentary bottom plan view of the cover showing the distributor attached thereto.

Referring to the drawing in detail it will be seen that 1 designates a hollow body having its upper portion open and having a groove situated in its lower wall so that the 40 hollow body may be positioned on a support such as an exhaust pipe of an internal combustion engine. Suitable dust packing 2 is situated in this groove so as to prevent the overheating of the body 1. A series of 45 spaced semi-circular staves 3 are arranged along the bottom of the body 1 and support a foraminous partition 4 which is preferably formed of two layers of screening which should be comparatively fine in mesh. 50 It will be noted that this partition 4 divides the hollow body into an upper and a lower compartment. In the upper compartment a sponge 5 or any suitable absorbent material is situated. An outlet nipple 6 is situated in one end wall of the body 1 adjacent 55

the upper portion of the partition 4 and extends into the interior of the lower chamber. A suitable drain cock 7 is provided in the lower chamber adjacent the bottom thereof.

A closure 8 is provided for the upper portion of the body 1 and a suitable gasket 9 will be interposed between this closure 8 and the body 1. This closure 8 will preferably be held in place by bolts and nuts 10. An 60 inlet nipple 11 extends through the closure 8 and preferably through the center thereof. A distributor 12 is attached to the lower face of the closure 8 so as to register with the nipple 11. This distributor 12 is formed 65 from a sheet of perforated metal or other suitable material and is bent so as to be semi-circular in transverse cross section while the ends thereof will be bent upwardly and terminate a relatively short distance 70 from the closure 8 so as to provide an overflow outlet for this distributor.

The pipe leading from the gasoline supply tank will be attached to the intake nipple 11 and the gasoline passing therethrough 80 will drip through the various apertures provided in the distributor 12 and will then pass through the sponge 5. While passing through the sponge 5 the gasoline will be thoroughly cleansed of all foreign matter 85 and will be free to pass through the foraminous partition 4. Any water which may be contained in the gasoline after having passed through the sponge 5 will naturally, through capillary attraction, run downwardly along 90 the wires of the foraminous partition rather than pass therethrough and will thus enter the lower chamber adjacent its lower portion and thus it will be seen that the gasoline in the lower chamber will naturally at 95 all times be in the upper portions thereof so as to pass through the outlet nipple 6 to the carburetor. Should the level of the water become higher than the outlet nipple 6 the drain cock 7 may be opened so that the 100 water may be drained from the lower chamber. It will also be readily seen that by removing the closure 8 all the interior mechanism of the filter may be readily removed and cleansed or replaced as may be desired. 105

Having thus described the invention what I claim as new is:—

In a filter, a hollow body, a series of spaced semicircular staves situated in the hollow body, a foraminous partition supported on 110

said staves so as to divide the hollow body into an upper and a lower chamber, a sponge or other absorbent material situated in the upper chamber, a distributer situated in the upper chamber, said upper chamber provided with an inlet and said lower chamber provided with an outlet.

In testimony whereof I affix my signature in presence of two witnesses.

WILLIAM C. STROWBRIDGE.
